UNITED STATES PATENT OFFICE.

CHARLES F. FRAZIER, OF SOUTH GREENFIELD, MISSOURI.

BRANDING IRON.

Application filed December 14, 1921. Serial No. 522,332.

To all whom it may concern:

Be it known that I, CHARLES F. FRAZIER, a citizen of the United States, residing at South Greenfield, in the county of Dade 5 and State of Missouri, have invented certain new and useful Improvements in Branding Irons, of which the following is a specification, reference being had to the accompanying drawings.

10 This invention relates to branding irons, and has for its object to provide a device of this character capable of being used for branding purposes for any length of time without interruptance previously necessary 15 in order to heat the branding iron.

It is another object of the invention to provide a device of this character wherein the branding iron is constantly heated and capable of being used similar to a lighting 20 implement, to make the branding characters necessary, without interrupting the branding operation for heating purposes.

It is another object of the invention to provide a device of this character including 25 a support and fuel reservoir and a nozzle adapted to discharge a flame directly into a branding member or iron, means being provided to regulate the temperature of the iron.

30 It is a further object of the invention to provide a device of this character wherein the handle member of the device also serves as a support for the fuel reservoir and the branding iron.

35 It is still a further object of the invention to provide a device of this character including a handle member to which a heating chamber is connected, said chamber having a branding iron engaged therewith and extending into the chamber, and a fuel supply 40 tank or reservoir provided by the handle and having a nozzle communicating therewith, said nozzle extending into the chamber to direct the flame thereof into the branding iron, said heating chamber serving as 45 heat insulating means and as a protector for the flame of the nozzle.

50 With these and other objects in view, the invention consists in the improved construction and arrangement of parts to be hereinafter more particularly described, fully

claimed and illustrated in the accompanying drawings, in which:—

Figure 1 is a perspective view of a branding iron constructed in accordance with 55 an embodiment of the invention;

Figure 2 is a front elevation of the structure shown in Figure 1; and

Figure 3 is a fragmentary sectional view 60 of the heating chamber, iron and nozzle.

Referring to the drawings, 5 designates a tank or reservoir adapted to hold liquid fuel such as gasoline, the top of said tank being provided with an inlet for the admission of liquid. Projecting from the upper 65 edge of the tank and automatically spaced from each other, are sockets 6 and 7, while projecting from the lower portion of the tank is a coupling member 8 to which a conduit or pipe 9 is connected, and through 70 which the fuel in the tank is discharged. Connected to the pipe 9, is an elongated nozzle 10 which serves as a burner for a valve chamber 11 at one end, said valve chamber having a port 12 in which one end 75 of the pipe 9 is disposed. A valve 13 is disposed within the chamber 11 and adapted to control the flow of fluid through the bore of the nozzle 10.

Projecting from the socket 6 of the tank 80 is an elongated handle 14, said handle extending a considerable distance below the tank and having its lower end portion disposed in a socket 15 carried by a base member 16. Projecting from the socket member 85 7 is a substantially arcuate brace 17, the opposite end of said brace terminating adjacent the bottom of the tank and in spaced relation to the bottom of the tank. In view of the length of the handle 14, it is possible 90 for the device to be conveniently grasped and at the same time it is rendered compact, as the tank is disposed inwardly of the handle.

In connection with the nozzle, a chamber 95 or housing 18 is provided, said chamber tapering from its intermediate portion to its ends so that in rear elevation the chamber is substantially a trapezoid. The front portion 19 and sides 20 merge substantially to 100 provide a semi-dodecahedron. The rear wall 22 of the chamber is provided with a

central opening 23 from which an annular collar or hood 23^a projects, said opening being of a diameter considerably greater than the diameter of the nozzle 10 and 5 through which the end of the nozzle extends, so that the flame at the end of the nozzle is confined within the chamber. At the same time, the opening in the rear wall 22 provides an air inlet for the flame. The 10 lower portion of the chamber serves as a heating compartment, while the upper portion serves as a cooling compartment, the cooling compartment being provided with a series of openings to permit the escape 15 of heat should the temperature become greater than that necessary for heating the iron.

The branding iron consists of a substantially T-shaped member including a head 20 25, and a central extension 26, the head 25 and extension 26 being hollow. The extremity of the extension 26 terminates adjacent the extremity of the nozzle 10 so that the flame of the nozzle is directed into 25 the extension through the medium of the air passing through the opening. In this way, the iron receives the direct force of heat, and as the nozzle is constantly supplied by the tank 5 the iron can be maintained at the same temperature indefinitely 30 so that the branding operation may proceed without interruptions for heating the iron. The end portion 27 of the iron is open, to permit the escape of heat to a large extent 35 and also the admission of air in the cooling process of the iron should the temperature become too great. This opening is controlled by a slide valve 27^a mounted in guides 28 carried by the base member 16, 40 a finger piece 29 being provided. The top of the chamber is provided with a socket 31 in which the lower end of the brace 17 is disposed. In this way the chamber as 45 well as the tank provides means for connecting the various parts of the device to each other and assist in rendering the same substantial and compact. The forward portion of the chamber 18 is provided with an opening 32 controlled by a plate 33, the 50 opening 32 being provided for lighting the device by inserting a match after the gasoline has been released by the valve 13. To assist in holding the parts rigid, braces 34 are provided, one of said braces connecting 55 the cooling chamber with the lower portion of the tank, the remaining brace connecting the valve chamber to the intermediate portion of the discharge nozzle.

In operation, the device is ignited as 60 above described by the insertion of a match in the chamber 13. The flow of gasoline may then be regulated by the valve 13 and after the iron 25 has been heated to the extent desired, the handle 14 may be grasped 65 by the operator and the entire device used

similar to a conventional form of writing implement, so that any character desired may be made. After the iron has been used for a considerable length of time and the heat of the iron increases, the slide valve 70 27 may be operated to permit the escape of heat by the admission of air, it being of course obvious that the upper portion of the head 25 communicates with the heating chamber so that the heat may escape from 75 the head into the cooling chamber.

From the foregoing it will be readily seen that this invention provides a novel form of branding iron, wherein the escape of heat generated within the device is prevented, and at the same time the flame of the nozzle is also prevented from coming in contact with any adjacent object, and as the heating of the iron is confined to the interior of the chamber, it is possible to 80 rapidly heat the iron to the temperature desired. In addition to this the chamber as well as the tank serves as connecting means to hold the various parts of the device together and as these parts are simple, the 90 device will last indefinitely.

What is claimed is:—

1. A branding iron of the character described comprising a reservoir, a handle member extending from one side of the reservoir, a brace projecting from the opposite side of the reservoir, a base member disposed beneath the reservoir, the opposite end of said handle being connected to the base, a chamber engaged with the opposite end of the base and said brace member, a branding iron carried by said chamber, and a burner carried by the reservoir and connected to the base, said burner extending into the chamber for heating the 100 branding iron.

2. A branding iron of the character described comprising a reservoir, a handle member extending from one side of the reservoir, a brace projecting from the opposite side of the reservoir, a base member disposed beneath the reservoir, the opposite end of said handle being connected to the base, a chamber engaged with the opposite end of the base and said brace member, a 110 branding iron carried by said chamber, and a burner carried by the reservoir and connected to the base, said burner extending into the chamber for heating the branding iron, and means carried by the lower portion of the chamber for regulating the temperature within said chamber and the branding iron.

3. A branding iron of the character described comprising a reservoir, a handle 125 member extending from one side of the reservoir, a brace projecting from the opposite side of the reservoir, a base member disposed beneath the reservoir, the opposite end of said handle being connected to the 130

base, a chamber engaged with the opposite end of the base and said brace member, a branding iron carried by the lower portion of the chamber, said branding iron being 5 hollow and having an extension projecting into the chamber and a burner connected to the reservoir and the base member, said burner extending into the chamber substan-

tially in alignment with the extension of the branding iron, whereby the flame of the 10 burner is directed into the hollow extension of the branding iron.

In testimony whereof I hereunto affix my signature.

CHARLES F. FRAZIER.
